UNITED STATES PATENT OFFICE.

JAMES BARLOW AND SPENCER M. ALPAUGH, OF TRENTON, NEW JERSEY.

DESIGN FOR TABLE-WARE.

SPECIFICATION forming part of Design No. 14,528, dated January 1, 1884.

Application filed October 29, 1883. Term of patent 3½ years.

To all whom it may concern:

Be it known that we, JAMES BARLOW and SPENCER M. ALPAUGH, of Trenton, in the State of New Jersey, have invented and produced a new and ornamental Design for Articles of Table-Ware, of which the following is a specification, reference being had to the accompanying drawing.

This drawing shows our design as applied to 10 a tea-pot; but we can and do apply our design to any article of table or toilet ware of suitable general configuration.

In this drawing, A is the body of the pot. B is the neck, and C the rim. D is the cover 15 or lid, provided with its handles E. E is the handle of the pot. The neck B is encircled by a band, B', representing wicker-work reaching almost to the rim. This rim is scalloped. The general shape of the pot is as shown, with 20 straight-lined sides suddenly contracting to form the neck and base, as shown at A'. The handle E is composed of the two arms E', connected by the bow or arch E''. These arms are thicker at their juncture with the body of the 25 pot and their union with the arch or bow than in the center, thus presenting both above and below an inwardly-curved outline. At the end farthest from the body they are beveled both above and below, thus presenting a half-

diamond shape pointing outwardly. Upon 30 either side of these arms is a depression corresponding in outline shape with the outline shape of the arms, and about the center of the arm, or nearly midway from the body of the pot to the bow or arch, is the representation 35 of a cord, E'', wrapped about said arm. The handle E of the cover is the same in general outline and design.

What we claim as our design, and desire to 40 secure by Letters Patent, is—

1. A design for table-ware, of the general body outline shape shown and described, and encircled by the wicker-work band B'.
2. A design for table-ware, of the outline shape shown and described, and encircled by 45 the wicker-work band B', provided with the handles E.
3. In a design for table-ware having the body outline shown and described, the handle consisting of the arms E', united by the bow E, and encircled by the ornament representing cords E''.

JAMES BARLOW.
SPENCER M. ALPAUGH.
